(57) **CLAIM**

The ornamental designs for sensors, as shown and described.

DESCRIPTION

FIG. 1 is a perspective view of a first embodiment of a sensor including a stand, showing our new design; FIG. 2 is a front view of the sensor shown in FIG. 1; FIG. 3 is a right side view of the sensor shown in FIG. 1; FIG. 4 is a left side view of the sensor shown in FIG. 1; FIG. 5 is a top view of the sensor shown in FIG. 1; FIG. 6 is a perspective view of a second embodiment of a sensor including a stand, showing our new design; FIG. 7 is a front view of the sensor shown in FIG. 6; FIG. 8 is a back view of the sensor shown in FIG. 6; FIG. 9 is a right side view of the sensor shown in FIG. 6; FIG. 10 is a left side view of the sensor shown in FIG. 6; FIG. 11 is a top view of the sensor shown in FIG. 6; FIG. 12 is a bottom view of the sensor shown in FIG. 6; FIG. 13 is a perspective view of a third embodiment of a sensor including a stand, showing our new design; FIG. 14 is a front view of the sensor shown in FIG. 13; FIG. 15 is a right side view of the sensor shown in FIG. 13; FIG. 16 is a left side view of the sensor shown in FIG. 13; FIG. 17 is a top view of the sensor shown in FIG. 13; FIG. 18 is a perspective view of a fourth embodiment of a sensor including a stand, showing our new design; FIG. 19 is a front view of the sensor shown in FIG. 18; FIG. 20 is a back view of the sensor shown in FIG. 18; FIG. 21 is a right side view of the sensor shown in FIG. 18; FIG. 22 is a left side view of the sensor shown in FIG. 18; FIG. 23 is a top view of the sensor shown in FIG. 18; FIG. 24 is a perspective view of a fifth embodiment of a sensor including a stand, showing our new design; FIG. 25 is a front view of the sensor shown in FIG. 24; FIG. 26 is a back view of the sensor shown in FIG. 24; FIG. 27 is a right side view of the sensor shown in FIG. 24; FIG. 28 is a left side view of the sensor shown in FIG. 24; and, FIG. 29 is a top view of the sensor shown in FIG. 24.

The details shown in broken lines in illustrated embodiments depict environmental subject matter only in those embodiments and form no part of the design claimed with respect to those embodiments. Back views of the sensors according to the first and third embodiments are not shown and form no part of the designs claimed for the sensors according to the first and third embodiments. Bottom views of the sensors according to the first, third, fourth, and fifth are not shown and form no part of the designs claimed for the sensors according to the first, third, fourth, and fifth embodiments.
